Primary Examiner — John A Voytek*(74) Attorney, Agent, or Firm* — June E. Rickey(57) **CLAIM**

The ornamental design for a tire as shown and described.

DESCRIPTION

FIG. 1 is a perspective view of a full tire including the tire tread of the present application;

FIG. 2 is a front view thereof;

FIG. 3 is a side view thereof;

FIG. 4 is an enlarged partial perspective view thereof;

FIG. 5 is an enlarged partial front view thereof; and,

FIG. 6 is an enlarged partial side view thereof.

The broken lines and the region therebetween defining the inner bead and the sidewall depict subject matter that forms no part of the claimed tire design, and are included for the purpose of illustrating the full tire. Likewise, the tire interior forms no part of the claim. The tread pattern is understood to repeat throughout the circumference of the tire so that top, bottom, and side views of the tire are the same as the illustrated front view. The other side view of the tire is identical to the illustrated side view.
